UNITED STATES PATENT OFFICE.

HERMAN IHLENBURG, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 14,576, dated January 29, 1884.

Application filed November 24, 1883. Term of patent 14 years.

To all whom it may concern:

Be it known that I, HERMAN IHLENBURG, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression, to 10 which reference is made; and it consists of a text-letter the heavy lines of which are shaded by the lighter lines, as shown, and ornamented by a light groundwork, as shown. In the B, E, F, H, I, J, K, L, M, P, R, T, U, V, W, Y, 15 and Z the upper left-hand termination of the letter is ornamented by the light curved line with heavy dot termination.

The character of the design is preserved in the lower-case and numerals, save that the groundwork ornamentation is omitted. 20

In connection with the font are shown a series of ornamental adjuncts placed upon the left hand and right hand of the numerals, and reference is made to the typographic impression, which shows fac-similes of the faces of 25 these ornamental adjuncts.

Having now set forth my invention, I claim as new—

The design for a font of printing-type, substantially as shown and described.

HERMAN IHLENBURG.

In presence of—

C. F. HUCH,

WM. B. MACKELLAR.
